DRYING OVEN

Nathan J. Greene, Worthington, and George C. Reese, Columbus, Ohio, assignors to National Electric Coil Company, Columbus, Ohio, a corporation of West Virginia

Application May 7, 1940, Serial No. 333,804

7 Claims. (Cl. 34—87)

The present invention relates to ovens and more particularly to ovens for drying coating material on wires.

One of the objects of the present invention is to provide an oven formed in two sections relatively movable to one another for forming a gap and to provide mechanism for bodily or translatable moving the oven and for simultaneously opening and closing the gap so that when the oven is moved in one direction the gap is opened to receive the wire, and is then closed after the wire is in the oven, and, when the oven is moved in the opposite direction the gap is opened for the purpose of removing the oven from about the wire and is then reclosed after the oven is moved away from the wire.

Still another object is to provide, in connection with a wire treating apparatus that affects the length of the wire, a spool for receiving the treated wire and a device for guiding the wire through the apparatus, which device is automatically movable in the direction of the change in length of the wire for maintaining a substantially constant tension on the wire and providing slack in the wire when the apparatus is shut down and prior to shrinkage of the wire.

Still another object is to provide a gas duct interconnecting a translatable movable oven and a relatively stationary support for the oven, which duct includes telescoping sections, one of which sections being connected with the interior of the oven and movable with the oven, and another of the sections being attached to the support so that gas may be withdrawn from the oven through the support.

It is also an object of the invention to provide mechanism for moving the wire through the oven as the oven heats the wire and a control device for causing the oven to be removed from about the wire when the mechanism moving the wire is stopped.

A further object of the invention is to provide a guide mechanism for a wet coated wire, which mechanism includes a member engaging the coated wire and a device for supplying a constituent, or constituents similar to the constituents of the coating on the wire for preventing deposition of the coating on the guide member.

Other and further objects and advantages will be apparent from the following description, ref-

erence being had to the accompanying drawings wherein a preferred form of embodiment of the present invention is clearly shown.

In the drawings:

5 Fig. 1 is a diagrammatic, plan view of an apparatus for coating wires:

Fig. 2 is a side view of an oven, forming a part of the apparatus illustrated in Fig. 1, for drying coating on a wire, part of the oven being broken away;

10 Fig. 3 is a view in section taken on line 3—3 of Fig. 2, but on a larger scale;

Fig. 4 is an end view of the oven shown in Fig. 2;

15 Fig. 5 is a view similar to Fig. 4 but showing parts of the oven in different positions;

Fig. 6 is a view similar to Fig. 4 but showing parts of the oven in still different positions;

20 Fig. 7 is a view, partly in section, of a wire guide;

Fig. 8 is a top view of a wire guiding mechanism, part of the mechanism being broken away;

Fig. 9 is a view similar to Fig. 8 but showing parts of the mechanism in different positions;

25 Fig. 10 is a view taken on line 10—10 of Fig. 9; and

Fig. 11 is a diagrammatic illustration of the control mechanism for the apparatus shown in Fig. 1.

30 Referring to the drawings, an apparatus 20 is shown for treating a wire 21 by wrapping insulating material about the wire, applying wet coating over the insulation and drying the coating as the wire is passed through the apparatus.

35 The untreated wire 21 is withdrawn from a spool 22, which spool is suitably mounted for rotation. Preferably a suitable brake is provided for maintaining a tension on the wire as the wire is unreeled from the spool. The wire first passes

40 through a mechanism 26 that wraps a suitable insulating material, such as glass cloth, about the wire. This type of mechanism is well known and it is therefore not described in detail. The mechanism 26 is driven by an electric motor 25, shown diagrammatically in Fig. 11. After the

45 wire is wrapped with insulation it passes through a device 27 which deposits a wet coating of varnish of any suitable type on the wire. The wire next passes through two electrically heated ovens 50 28 arranged in tandem, which ovens dry the

varnish. The wire then passes around a pulley wheel 30 and then through a second varnish applying device 31, which device is similar to the device 27. The wire then passes through two additional oven 28 which dry the second coat of varnish. Guide devices 29 support the wire 21.

The wire is drawn through the apparatus 20 by a rotating drum 34 that is driven by the motor 25, which motor also drives the wrapping mechanism 26. The wire is looped about the drum 34 to provide traction between the drum and wire. As the wire leaves the drum 34 it is wound on a spool 35, which spool is rotated in the proper direction by suitable mechanism not shown. A threading device, not shown, is employed to cause the wire to be evenly disposed on the spool 35. The rate at which the wire is drawn through the apparatus 20 is such that the varnish will be dried during movement of the wire through two of the ovens 28. It is desirable at times to stop the movement of the wire 21 through the apparatus 20 during the treating of the wire, and in this event it is necessary to remove the heat from the wire to prevent overheating of the varnish and the destruction of the insulating material. This can be accomplished by separating the wire and the ovens either by removing the wire from the ovens or the ovens from the wire. In the present embodiment, the ovens 28 are removed from the wire automatically.

The ovens 28 are mounted on supports comprising inverted channel members 36 having an upright member 39 at one end and a second upright member 40 at the opposite end. The upright members 39 and 40 are braced by suitable flanges indicated at 41. The member 36 cooperates with the floor to form a conduit 37 extending from one end of the member 36 to the other. One end of the conduit is closed by a wall 38. Preferably two ovens 28 are arranged end to end with the edges of the open ends of the members 36 of the supports abutting one another for connecting the conduits 37. When the ovens are arranged in this manner, two uprights 40 will lie adjacent one another as illustrated in Fig. 2.

An elevating device 44 is mounted on each of the members 36 and each device comprises a cylinder 45 and piston 46. The piston 46 is raised by air admitted into the lower end of the cylinder 45 through a conduit 193, and the piston may be lowered in the cylinder by venting the air from the cylinder, through a conduit 194. These conduits are illustrated diagrammatically in Fig. 11.

A tubular frame 48 is mounted on the end of the piston 46 by a bracket 50. The frame 48 is formed by an inverted channel shaped member 52 and a plate 53 welded over the open side of the member 52. Skirt members 54 are also welded to two opposite sides of the channel member 52. The top wall of the member 52 is perforated as at 55, the perforated area extending substantially the length of the frame 48. The ends of the tubular frame 48 are closed by two bracket plates 57 welded to the ends of the frame.

Two openings 58 are formed in the bottom wall of the tubular frame 48 and sleeves 59 are connected around the openings, which sleeves extend downwardly. These sleeves are welded to the skirts 54. The top wall of the channel member 36 is formed with two openings 60, which openings are in alignment with the openings 58. A sleeve 61 is secured around each of the openings 60 and extends upwardly to receive the 75

sleeves 59. The outside diameters of the sleeves 59 are slightly less than the inside diameters of the sleeves 61 so that the sleeves 59 telescope within the sleeve 61. Thus the conduit 37 is connected with the interior of the tubular frame 48. Valves 62 are provided at the openings 60.

Two downwardly extending brackets 64 are attached to the frame 48 at each end thereof and a pin 65 is supported by the brackets 57 and 64 at the lower ends of the brackets. The pins 65 extend beyond the ends of the frame 48 and between flanges 66 of two vertically extending angle irons 67 two of which irons are attached to the uprights 39 and 40, respectively. The pins 65 cooperate with the flanges 66 for guiding the frame 48 vertically.

The heating portions of the ovens 28 comprise two relatively long and movable sections 70, which sections have two surfaces that confront one another when the sections are brought together as illustrated in Fig. 3. The sections 70 are formed of a refractory material 71 encased in suitable sheet metal covering 72, which covering is reenforced at the edges by angle irons 73. The bottoms of the sections 70 are reenforced by plates 74. The confronting surfaces of the sections 70 have semi-elliptical troughs 75 extending lengthwise thereof for forming an elliptical, substantially tubular opening through the oven when the two sections 70 are brought together. The walls of the troughs 75 are covered with suitable reflector sheets 76 for reflecting heat to the central portion of the opening through the oven when the oven is closed. The ends of the troughs 75 are closed by rectangular plates 78, which edges coincide with the end edges of the sections 70. The confronting edges of the plates 78 are notched as at 79 to form openings in each end of the oven through which the wire 21 may pass while the oven is closed.

Electric heating elements 80 are supported in the troughs 75 by rods 82, which rods are suspended in slots formed in vertical straps 83 and these straps are secured to the walls of the troughs. The heating elements 80 are connected with power mains 84 by leads 85.

The oven sections 70 are pivotally mounted on the pins 65 by brackets 88 secured to each end of the sections so that the sections may be swung outwardly with respect to one another as illustrated in Fig. 5. The brackets 88 comprise metal plates that are welded to the end plates 78. The lower ends of the brackets 88 are journaled on the pins 65. Thus the oven sections are raised and lowered when the frame 48 is raised and lowered, respectively, by the operation of the piston 46.

One of the two brackets 88, at each end of the oven, is shorter than its complementary bracket so that the edges of the brackets may be brought together as illustrated in Figs. 4 and 6. The shortened brackets are connected to the pins 65 by metal straps 90 welded to the lower ends thereof.

The ends of the oven sections 70 are tied to the uprights 39 and 40, respectively, by links 100. The inner ends of the links are pivotally secured to the uprights by pin bearings 102 and the outer ends of the links are connected to the sections 70 by pin bearings 103. When the frame 48 is lowered from its raised position, as illustrated in Fig. 4, the links 100 separate the sections 70, as illustrated in Fig. 5. The separation of the sections 70 forms a gap leading from the interior of the oven to the exterior thereof, which gap

receives the wire as the oven is lowered from the wire. As the oven sections are further lowered the links draw the sections together to substantially close the oven, as is illustrated in Fig. 6.

Brackets 105 are attached to the brackets 88 above and below the links 100 and adjusting bolts 106 are threaded in these brackets for forming stops for the links 100. The links 100 engage the ends of the bolts 106 and limit vertical movement of the ovens.

An air seal is provided between the bottom walls 14 of the sections 70 and the side walls of the frame 48. This seal comprises rubber breaker strips 108 that are secured to the bottom walls of the sections 70 by longitudinally extending angle irons 109, and which breaker strips frictionally engage the side walls of the tubular frame 48. The angle irons 109 are secured to the plates 74 by bolts, not shown. When the ovens are in their raised or lowered positions, as illustrated in Figs. 4 and 6, respectively, the seal closes the space between the bottom of the oven sections and the perforated top wall of the frame 48.

Gases produced by baking of the varnish on the wire 21 are removed from the oven by a fan 110 that is connected by suitable conduits, not shown, to the ducts 37 formed by the support members 36 and the floor. As the fan is operated air is drawn through the openings between the oven sections 70 and into the tubular frames 48 through the apertures 55. The air carries the gases from the ovens through the sleeves 57 and 61 into the conduits 37. The fan 110 then exhausts the air and gases into the atmosphere. Preferably the fan 110 is operated during the time that the ovens are energized by an electric motor 111.

Referring to Fig. 7, one of the wire guide devices 29 is shown in detail. The device 29 includes a supporting plate 114 and a roller 115 is mounted on the plate 114 by a suitable bearing 116, which roller supports the wire 21 passing through the apparatus 20. The plate 114 is adapted to be attached to the uprights 39 or 40 of the ovens 28. The periphery of the roller 115 is maintained moistened with a suitable thinner that forms a constituent of the varnish that is applied to the wire 21 at 27 and 31 so that varnish on the wire passing over the roller will absorb the thinner and not adhere to the roller. This thinner is applied to the roller through a pipe 118 mounted in an opening through the plate 114, which pipe is connected at one end to a reservoir 120 and the other end opens into a trough 121. The liquid thinner is placed in the reservoir and is fed to the trough 121 through the pipe 118. A suitable wick 122 is placed in the trough 121 and engages the lower edge of the roller for transferring thinner to the roller as the roller is rotated by the wire 21.

The pulley wheel 30 is mounted on mechanism that moves the wheel 30 in the direction of expansion and contraction of the wire 21, caused by changes in temperature of the wire. This mechanism includes a base 125 that is attached to a wall or other suitable support, which support is not shown. A U-shaped bracket 126 is secured at its open ends to the base 125. Two members 127 and 128 are pivoted together at 129 to form a hinge. The free end of the member 127 is attached to the yoke of the member 126 and a shaft 130 is attached to the free end of the member 128 by brackets 131. The pulley wheel 30 is rotatably mounted on the shaft 130 and is

supported by a suitable anti-friction bearing 132, disposed between the upper bracket 131 and the wheel 30. A cylinder 135 and piston 136 are mounted on the base 125 by a pivotal support 137. This support 137 permits the cylinder to swing. The rod of the piston 136 extends through openings in the members 127 and 128 and is pivotally connected to the shaft 130. Air, under pressure, is admitted to the left hand end of the cylinder 135, as viewed in Fig. 11, through pipe 138 and to the right hand end of the cylinder through a pipe 139. When air is forced into the right hand end of the cylinder 135 the piston moves the wheel 30 in the direction of expansion of the wire 21, as is illustrated in Fig. 9, and when air is forced into the left hand end of the cylinder 135 the piston moves the pulley wheel 30 to the position shown in Fig. 8, or in the direction of contraction of the wire 21. The flow of air to the cylinder 135 is controlled by valves operated simultaneously with the raising and lowering of the oven sections 70. These valves are described hereinafter. The travel of the piston 136 in one direction is equal to the expansion of the portion of the wire 21 heated by two of the ovens.

The periphery of the pulley wheel 30 is maintained moist by varnish thinner, applied by a suitable device 140, which device may be constructed similarly to the devices 29.

Referring to Fig. 11, the control circuits for the apparatus 20 are illustrated diagrammatically, the circuits being deenergized. Electric current is supplied to the apparatus by two mains 146 and 147 through a suitable double pole switch 148, which switch is closed manually. The heater elements 80 of the ovens 28 and the motor 111 for the fan 110 are connected in parallel circuits and are energized when the switch 148 is closed. The circuit for the heating elements 80 is established from main 146 through switch 148, wires 149, 150, 151, elements 80, wire 152 and switch 148 to main 147.

The fan motor 111 is energized by current traversing wires 149 and 150 to one side of the motor, and wires 153, 154 and 152. Thus the fan 110 will operate during the time the oven heaters are energized.

The motor 25 for driving the wire wrapping mechanism 26 and the drum 34, is adapted to be energized by closing any one of the normally open switches 156, which switches may be located at convenient points along the apparatus 20. The closure of any one of the switches 156 establishes a circuit from wire 149 through the closed switch 156 to wire 157, coil 158 of relay 159, wire 160, normally closed switches 161, wire 162, coil 163 of relay 164, and wires 165, 154 and 152. The relay 159 closes a switch 166 to complete a holding circuit around the switches 156. This holding circuit is established from wire 149 through wires 167 and 168, switch 166, wire 169 and coil 158. The relay 164, when energized, opens switch contacts 170 and closes switch contacts 171 for establishing a circuit from wire 168 through wire 174, switch contacts 171, wire 175, coil 176 of relay 177 and wires 178, 154 and 152. The relay 177, when energized, closes the switch 179 for completing the circuit for the motor 25, which circuit includes wire 149, motor 25, wires 180, 178, 154 and 152. Thus the motor 25 is energized to cause the wire 21 to be moved through the apparatus 20 and to drive the mechanism 26 to wrap insulation on the wire.

The closing of the contacts 171 also establishes a circuit from wire 175 through wire 181, through the coil 182 of a magnetic valve 183 through wire 184 to wires 165, 154 and 152. The energization of coil 182 opens the valve 183 to admit air under pressure from a suitable source, not shown, through a pipe 190 to the manifold 192, which air passes into the lower end of the cylinders 45 through pipes 193 interconnecting the manifold 192 and the cylinders. Conduits 194 interconnect the cylinders 45 and an exhaust manifold 195. The manifold 195 is closed by a magnetic valve 196, which valve is closed while the contacts 170 are open. The pistons 46 raise the oven sections 70 so that the sections are enclosed about the wire 21.

Air from the manifold 192 is also forced into the right hand end of the cylinder 135, as viewed in Fig. 11, through a throttling valve 198 and pipe 139 for causing the pulley wheel 30 to be moved in the direction of expansion of the wire. Air is vented from the left side of the piston 136 through the pipe 138, throttling valve 199, pipe 200 and through a two-way valve 201, which valve is positioned to discharge air from pipe 200 to the atmosphere. The air pressure supplied through the conduit 190 maintains the ovens 28 in their raised positions, as illustrated in Figs. 2, 3 and 4.

In case it is desirable to deenergize the motor 25 for any reason, any one of the switches 161 may be opened for breaking the circuits of the relays 159 and 164. This deenergizes the relay 177 and opens the motor switch 179. The coil 182 of the valve 183 is also deenergized and the valve is closed. The pistons 46, however, will remain in their raised positions because the exhaust manifold 195 is closed by the valve 196.

When the relay 164 is deenergized, the contacts 170 are closed and a circuit is established through the coil 210 for a time delay relay 211, which circuit is established through the wires 167, 212, coil 210, wires 213 and 154. After a predetermined time period has elapsed, the relay 211 closes the switch 214 for completing a circuit through wires 167, 215, 216, coil 217 of valve 196, wires 218 and 219, switch 214, wires 213, 154 and 152. The coil 221, of the magnetic valve 201, is connected in parallel circuit with coil 217 as it is connected to the wires 215 and 219.

The energization of the coil 217 of the valve 196 opens the exhaust manifold 195 to vent the air from the cylinders 45 for causing the ovens 28 to be lowered by gravity to the position shown in Fig. 6. Simultaneously, the energization of coil 221 of valve 201, causes the two-way valve to rotate to a position in which the port thereof, leading to the atmosphere, is closed and another port connects a pipe 223 to pipe 200. Pipe 223 is connected to pipe 190, and air is now admitted to the left side of the piston 136 through the throttle valve 199, to cause the pulley wheel 30 to be moved in the direction of contraction of the wire when the oven sections 70 are moved from about the wire. Air is vented from the right hand side of the piston 136 through pipe 139, valve 198, manifold 192, pipes 193, cylinders 45, conduits 194 and manifold 195.

The speed of movement of the pulley 30 in either direction is controlled by the flow of air through the throttle valves 198 and 199, and this speed is computed to correspond to the rate of expansion and contraction of the wire, during

the heating and cooling thereof, so that the wire is maintained slightly taut at all times. Also, by causing the pulley 30 to move in the direction of the contraction of the wire 21, the wire 5 will not be stretched away from the wrapping mechanism 26 after the mechanism has stopped. Otherwise, when the operation of the wire coating apparatus is temporarily halted, a gap would be formed in the insulation wrapping 10 on the wire, due to the wire, on cooling, stretching away from the inoperative wrapping mechanism.

The wire wrapping mechanism 26 and drum 34 will coast for approximately six seconds, for example, after the motor 25 is deenergized, therefore the time delay relay 210 is adjusted so that the ovens will not be lowered from about the wire 21 until the wire is substantially stopped.

It is apparent that fluid other than air might 20 be used to operate the pistons 46 in the cylinders 45 or the piston 136 in the cylinder 135.

While the form of embodiment of the present invention as herein disclosed constitutes a preferred form, it is to be understood that other forms might be adopted, all coming within the 25 scope of the claims which follow.

We claim:

1. In combination, an oven including two elongated sections, said sections being adapted 30 to form a heating chamber when adjacent one another, said heating chamber being open along one side thereof; means for moving one of said sections relative to the other for opening said chamber; an elongated hollow member extending along said one side of the chamber formed by said sections, said hollow member having an opening in registration with the opening in said chamber for forming a passage between the chamber and interior of said hollow member; a breaker strip carried by said one section, said 35 breaker strip being arranged to frictionally engage a side of said hollow member when said one section is moved adjacent the other section for forming a heating chamber; and means for withdrawing gas from said hollow member.

2. In combination, means forming an oven having an inlet opening and an outlet opening for the passage of a wire or the like through the oven; mechanism for moving the wire or the like 40 through said openings; power operated means for driving said mechanism, said mechanism being adapted to coast to stopping position after the power operated means is rendered ineffective; mechanism for causing relative movement 45 to be imparted between the wire and the oven for disassociating the entire wire from heat transfer relation with the oven; and control apparatus for said mechanisms, said apparatus including means for rendering the power operated means ineffective, time delay means for delaying the starting of the second mentioned mechanism until the first mentioned mechanism is substantially stopped, and means rendered operative by the first mentioned means of the control apparatus for rendering the time delay 50 means operative.

3. In combination, means forming an oven having two sections, said sections cooperating to 55 form an elongated passage having heat radiating walls, said passage being adapted to receive a wire or the like extending longitudinally through the passage; mechanism for moving the said wire or the like through the passage longitudinally; mechanism for moving said sections laterally 60 with respect to the wire for disassociating the

wire from heat transfer relation with the oven; and control apparatus for said mechanisms, said apparatus including means decreasing operation of the first mentioned mechanism and after a predetermined time after said decrease, means rendered operative by the means of the control apparatus, for rendering the second mentioned mechanism operative.

4. In combination, an oven comprising a plurality of complementary sections; and mechanism for bodily moving the oven from one position to another position and for moving the sections first away from one another and then toward one another while the oven is bodily moving from said one position to said other position, 10 said mechanism including a pivot for one section, a stationary support forming a stationary guideway for said pivot means for moving said pivot along said guideway from one position to another position, and means including a guide 20 member having a part fixedly associated with said support and a part fixedly associated with said one section for causing swinging movement to be imparted to said one section from and toward said other section about said pivot as the pivot moves along said guideway from said one position of the pivot to said other position thereof.

5. In combination, an oven comprising a plurality of complementary sections; and mechanism for bodily moving the oven from one position to another position and for moving one of the sections first away from and then toward another section while the oven is bodily moving from said one position to said other position, 30 said mechanism including a pivot for said one section, a support for said pivot, means for moving said pivot in a straight line from one position to another position, a link connected at one end of said one section and a pivot for the other end 40 of said link, a support for said second mentioned pivot, the first mentioned pivot being movable

5 relative to the second mentioned pivot, said link swinging said section from and toward the other of said sections when the first mentioned pivot moves in a straight line from said one position thereof to said other position thereof.

6. In combination, an oven comprising two complementary sections; means for pivoting said sections for permitting said sections to be swung relative to one another; a link connected at one end to one of said sections; a second link connected at one end to the other of said sections, the opposite ends of said links extending toward one another; means for fixedly pivoting said opposite ends of said links; and means for moving the first mentioned pivoting means relative to the second mentioned pivoting means for causing said links to be rotated about the pivoting means therefor in opposite directions for swinging said sections relative to one another.

7. In combination, a horizontally elongated oven having a heating chamber, said heating chamber being open along one side thereof; a horizontally elongated frame supporting said oven, said frame forming an elongated chamber, said frame chamber being open along one side thereof, the openings in said chambers registering with one another; an elongated supporting base for the frame arranged below and parallel with the frame, said base forming a horizontally disposed tubular chamber; an open top tube extending upwardly from the base toward the frame and communicating with the interior of the base chamber; an open bottom tube extending downwardly from the frame and communicating with the frame chamber, said tubes telescoping with one another; mechanism supported by the base for moving the frame vertically; and means for exhausting gases from the base chamber.
